UNITED STATES PATENT OFFICE

158,012

SPOON FISHING LURE

Lewis G. Rice, Montague, Mich.

Application June 23, 1949, Serial No. 3,490

Term of patent 7 years

(Cl. D31—4)

To all whom it may concern:

Be it known that I, Lewis G. Rice, a citizen of the United States, residing at Montague, in the county of Muskegon and State of Michigan, have invented a new, original, and ornamental Design for a Spoon Fishing Lure, of which the following is a specification, reference being had therein to the accompanying drawing, forming part thereof, in which

I claim:

The ornamental design for a spoon fishing lure, as shown.

LEWIS G. RICE.
